JOHN NILSEN SELVIG, OF CHICAGO, ILLINOIS, ASSIGNOR TO WESTERN ELECTRIC COMPANY, INCORPORATED, OF NEW YORK, N. Y., A CORPORATION OF NEW YORK.

STRAND-REELING APPARATUS.

Application filed July 1, 1926. Serial No. 119,855.

This invention relates to strand reeling apparatus, and more particularly to a continuously operating reeling or take-up apparatus.

5 In apparatus of this character the strand being drawn from a source of supply and wound upon a rotating take-up reel is usually transferred from the take-up reel which has been filled to an empty rotating 10 take-up reel without stopping the apparatus. This abrupt transference of the strand from a large diameter reel to a relatively small diameter reel it will be apparent, subjects the strand to an extreme range of tension 15 values, which in the case of some strands, depending upon their diameter or composition, would cause a breakage thereof or impart a deleterious strain thereto.

The primary object of this invention is the 20 provision of reeling apparatus of the aforementioned type wherein a substantially uniform predetermined tension is maintained at all times upon a strand during the winding thereof and particularly during the transfer 25 of the strand from a full take-up reel to an empty one while the reeling apparatus continues to function.

In accordance with one embodiment of this invention as adapted to the continuous 30 reeling of wire and particularly of pulp covered wire, there is provided a pair of rotatable take-up reels operatively connected through friction disc clutch members with a common constantly rotating driving mechanism, the clutch members being constantly engaged face to face with each other when the apparatus is operating but variable as to pressure between them, which variation in pressure is controlled through the agency 35 of a governing device comprising a pair of sheaves having an interposed rotatable spring controlled member with which the travelling wire is associated.

More specifically the wire in traveling 45 from the source of supply to the take-up reel passes around one of the sheaves and then a third sheave mounted with its axis perpendicular to the axis of the aforementioned sheave upon the interposed spring controlled member, and then around the other sheave in a direction opposite to its direction around the first sheave, and thence to the take-up reel. The movement of the spring controlled member, between the two 50 sheaves, in response to any tendency of the

predetermined tension upon the wire to vary, is transmitted to the friction disc clutch members through a system of very sensitively balanced levers operatively associated with the governing device.

Other objects and advantages of this invention will more fully appear from the accompanying detailed description taken in connection with the accompanying drawings, in which

Fig. 1 is a fragmentary front view of a continuously operated reeling apparatus embodying the features of this invention;

Fig. 2 is a side view thereof, partly in section;

Fig. 3 is an enlarged fragmentary section on the line 3—3 of Fig. 1 looking in the direction indicated by the arrows;

Fig. 4 is a section on the line 4—4 of Fig. 3 looking in the direction indicated by the arrows;

Fig. 5 is a plan view thereof;

Fig. 6 is a fragmentary enlarged detailed section view through the take-up reel arbor;

Fig. 8 is a fragmentary enlarged view of the take-up reel stop friction link;

Fig. 9 is a section on the line 9—9 thereof looking in the direction indicated by the arrows;

Fig. 10 is a skeleton view, partly in section, of the clutch controlling mechanism and the take-up drive, and

Fig. 11 is a fragmentary view of the mechanism illustrated in Fig. 10 showing the position assumed thereby should the wire break during the reeling operation.

The reeling apparatus illustrated in the drawings and to which this invention has been applied comprises two vertically arranged units 15 and 16 positioned one above the other and carried upon a single supporting frame 17. The units 15 and 16 are of substantially identical construction, each comprising a pair of power driven take-up reels 18 and a reciprocal wire distributing mechanism 19 for laying the wire in close, even spirals across the face of the reels, the entire apparatus being operated from an electric motor 22 carried upon the rear face of the frame 17. Each of the units 15 and 16 includes a main drive shaft 23

(Fig. 2) which in the operation of the apparatus rotates at a constant speed. Fixed to the shafts 23 are sprocket wheels 24 which are driven from a sprocket wheel 25 secured to the shaft of the motor 22 by a chain 26. Since the drive from the main drive shaft 23 of each unit to the associated take-up reel arbors is identical, the following description of the lower unit 16 also applies to the upper unit 15. Secured to the shaft 23 is a gear 28 meshing with a gear wheel 29 (Figs. 1 and 10) secured to a sleeve 30 rotatably carried upon a journal 31 mounted upon a take-up drive housing 32, the sleeve 30 being suitably secured against longitudinal displacement upon the journal 31. The sleeve 30 at its greatest diameter and upon its left hand side as viewed in Fig. 10 is provided with a friction clutch face 33. In axial alignment with the sleeve 30 and arranged for rotatable and longitudinal movement within an opening formed in the journal 31 is a spindle 35 which is rotated independently of the sleeve 30 and has pinned thereto at sleeve 36 having secured at its greatest diameter and upon its right face (Fig. 10) a ring 37 composed of any suitable friction material which with the opposed face 33 of the sleeve 30 forms a friction clutch. In suitable spaced relation upon the spindle 35 is a pair of gear wheels 38 and 39, the gear wheel 38 being integral with the sleeve 36, while the gear wheel 39 is independently pinned to the spindle 35. The left end of the spindle 35 is provided with a portion 42 of reduced diameter which is positioned within the bore of a sleeve 43 and spaced from the wall thereof, the sleeve being reciprocally mounted within a recess 44 formed in the housing 32. The sleeve 43 is supported at its left end upon a collar 45 carried upon the extreme left end of the spindle 35 and at its right end upon the periphery of an anti-friction bearing 46 mounted upon a shouldered portion 47 of the spindle 35. The recess 44 is closed at its left end by a plug 51 threaded thereto. At a point directly above the spindle 35, the periphery of the sleeve 43 is provided with gear teeth cut in the form of a rack 52. Journalled in a recess 53 formed in the housing 32 is a shaft 56 provided with gear teeth 57 upon an enlarged portion thereof, the teeth 57 meshing with the teeth 58 of the rack 52. One end of the shaft 56 extends from the housing 32 and fixed thereto is a lever 58, which in response to an associated mechanism to be described hereinafter and actuated during the reeling operation serves to vary the driving pressure between the opposed faces of the friction clutch comprising the ring 37 and the face 33 of the sleeve 30, and thus maintains a substantially uniform predetermined tension upon the wire at all times.

This completes the description of the drive from the motor 22 to the spindle 35 carrying the gears 38 and 39, which, as will be shortly described, drive direct to their associated take-up reel and it will be apparent that the speed of the gears 38 and 39 will vary with the driving pressure between the opposed faces of the friction clutch members, which in turn is controlled by the varying speed of the reel during the reeling 75 operation.

The means for supporting the take-up reels 18 upon the frame 17 in operative relation with their associated driving gear 38 or 39 and for readily mounting them upon and removing them from the apparatus, will now be described. Referring to Figs. 1, 2, 6 and 7, a pivotal arm 60 is provided for each take-up reel, the reel being rotatably supported at the upper end thereof, the lower ends of the arms 60 being pivoted to the frame 17 as indicated at 61 (Fig. 1). The reels 18 may be of any construction, being preferably made of sheet steel and comprising an axial drum member 62 with heads or flanges 63 disposed at opposite ends thereof. Secured to each flange 63 is an axial hub member 64 provided with an inwardly extending annular portion 67, the inner end faces of which cooperate with means to be presently described for locking the reels from longitudinal movement upon their supporting arbor. Rotatably journaled upon anti-friction bearings 68 and 69 suitably positioned in a recess 70 provided in a head portion 71 upon the upper end of the arm 60 is a spindle 72. Secured for rotation upon the spindle 72 is a gear wheel 75, the anti-friction bearing 69 being secured to a shouldered portion 76 provided upon the hub thereof. Clamping nuts 77 threaded onto threaded portions provided upon the spindle 72 serve to retain the bearings 68 and 69 in their assembled position, as shown on Fig. 6 of the drawings. Upon the left end of the spindle 72 is a sleeve 78 which is secured to the spindle by a pin 79, its right end abutting a shoulder formed upon the spindle. The diameter of the sleeve 78 and the greatest diameter of the spindle are such that they slidably fit within the bore of the hub members 64 provided upon the reel 18. Slidably carried within an axial opening 82 in the right end of the spindle 72 is a pin 83 equipped at its outside end with a knob 84. The pin 83 is limited in its longitudinal movement in the opening 82 by a pin 85 passing through the spindle 72, a slot 86 of suitable length being formed in the pin 83 for limiting the movement thereof. The spindle 72 at a point adjacent the left end of the pin 83 is provided with a pair of diametrically opposed slots 89 (Fig. 7), in each of which is positioned a dog 90. A right angle extension upon each dog 90 at 130

arm 60 during the movement of the latter from the full line position shown in the drawings to a point where it assumes a vertical position indicated by the dotted line 122. 5 The operator is thus relieved from all effort to hold back the weighted arm 60 after it passes the vertical position. The links 109 and 110 in their dotted line operated position (Fig. 2), it will be observed, assume a substantially straight line. Upon removing a filled reel 18 from its spindle and replacing it with an empty one in the manner hereinbefore described, the operator grasps the handle 101 and rocks the arm 60 to its full line position. During the later movement, the links 109 and 110 pivot about the bolt 113 in a direction opposite to their movement just described. The disc 118 during the return movement is stationary relative to the link 110, the plunger 121 moving away from the tooth 119 and onto the periphery of the disc 118, thus no friction occurs between the discs 118 and 120, the link 109 freely turning about the bolt 113. 25 The clutch governing device for maintaining a substantially uniform predetermined tension at all times upon the wire traveling between the source of supply, which may be a capstan (not shown) and the take-up reel 18 will now be described.

Referring to Figs. 1 and 2, at the top of the frame 17 is mounted a standard 124 and rotatably journaled upon an overhanging portion thereof are wire guide pulleys 125, which receive the wire from the supply source and guide it to the clutch governing devices. Rotatably journaled upon the standard 124 are a pair of horizontally disposed spindles 126 (Fig. 3), one of the pulleys 125 and one of the spindles 126 being operatively associated with each of the reeling units 15 and 16. Adjustably secured by a set screw (not shown) to the standard 124 is a sleeve 127 and attached thereto is a sleeve 129 within which is rotatably journaled the spindle 126. Rotatably journaled upon the sleeve 129 is a sheave 130 and spaced therefrom and similarly mounted upon the spindle 126 at the right end thereof, as viewed in Fig. 3, is a sheave 131. Also rotatably journaled upon the sleeve 129 intermediate the sheaves 130 and 131 is a housing member 132 which is fixed for rotation with the spindle 126 at the right end thereof (Fig. 3) by a key 133. The housing 132 is open at both ends, the sheaves 130 and 131 serving to close the ends thereof, as clearly indicated in Fig. 3. The housing 132 is yieldably connected to the sleeve 129 by a long spiral clock spring 135 which at its inner end is secured to the sleeve 129 as indicated by the numeral 136, its outer end being secured to the housing 132 as indicated by the numeral 137 (Fig. 4). The sleeve 127 is provided with a disc-like por-

tion 138 at its right end which is provided with an internal annular shoulder adjacent its periphery adapted to cover the periphery of one flange of the sheave 130, the opposite flange being similarly covered by 70 a plate 139 and the housing 132. The wire guiding surface of the sheave 131 is also covered at its inside edge by the housing 132 and the plate 139, all for the purpose of preventing the wire from becoming entangled inside of the governing device if it should move off of the peripheral guiding surface of the sheaves 130 and 131. Rotatably mounted upon the plate 139 within a depression 142 thereof (Fig. 4) and at 75 right angles to the sheaves 130 and 131 is a sheave 143. The wire guiding surfaces of the sheaves 130, 131 and 143 are substantially in alignment so that the wire, as will be more fully described hereinafter, is 80 adapted to pass from the sheave 130 to the sheave 143 and thence to the sheave 131 in a horizontal plane with the governing device in the position shown in the drawings. Secured for rotation to the spindle 126 85 at its left end (Fig. 3) is a cam 144 and riding upon the peripheral face thereof is a roller 145 (Fig. 10) carried upon the upper end of a lever 146, the lower end of the lever being pivotally supported between 90 the arms of a bifurcated lever 147 at a point 148. The lever 147 is pivotally mounted upon a pin 149 fixed to an arm 150 (Fig. 2) extending from the standard 124. The lever 146 near its pivot point 148 is 95 provided with a projecting arm 152 which in the normal position thereof as shown in the drawings, particularly Fig. 10, rests at its lower surface upon the long arm of the bifurcated lever 147. A tension spring 153 secured at opposite ends to lugs 154 formed upon the levers serves to draw the arm 152 and the long arm of the lever 147 into engagement. Pivotally connected to the long 100 arm of the lever 147 and depending therefrom is a link 155, the lower end of which is pivotally connected to one end of a rocker arm 156 pivotally supported upon the top surface of the frame 17 by a bracket 157. Extending through an opening provided in the left end of the arm 156 is the upper end of a downwardly extending link 158, the opposite end of which is pivoted to the lever 110 158 hereinbefore described in connection with the details of the friction clutch. Upon the upper end of the link 158 is threaded a pair of nuts 161 and mounted upon the link 158 between the end of the rocker arm 156 and the nuts 161 is a coiled compression spring 162 which forms a yieldable connection between the rocker arm 156 and the link 158. A similar spring 163 of greater force surrounding the link 158 adjacent its lower end and positioned between a pair of nuts 164 threaded upon the link and a sta- 115 120 125 130 135

the left end thereof engages the left end of the pin 83, and when the reel 18 is locked upon the spindle 72, as indicated in Fig. 6, a shoulder 91 upon each of the dogs 90 rests 6 against the right end of the sleeve 78 which extends slightly over the left end of the slots 89. The dogs 90 in this position it will be observed at their right ends projects through the slots 89 and outside of the periphery of the spindle 72, an angular face 92 contacting with the inner end face of the inwardly extending annular portion 67 of the axial hub member 64 secured to the right end of the reel 18. Carried in the opening 82 of the spindle 72 at the left of the slots 89 is a spring pressed pin 93 which serves to retain the dogs 90 in their normal position as shown in Figs. 6 and 7 of the drawings, in which position it will be apparent that the reel 18 is prevented from longitudinal movement upon the spindle 72 by the dogs 90 engaging the inner end face of portion 67 of the member 64, as hereinbefore described. To release the reel from the spindle 72, the operator presses the knob 84 inward against the force of the spring pressed pin 93 and in so doing the dogs 90 are rocked inward due to the right angle extensions thereof positioned between the opposed ends of the pins 72 and 93. The dogs are thus drawn within the periphery of the spindle 72 in which position it will be apparent that the reel may be readily withdrawn from the spindle. A cap member 94 is secured to the head portion 71 of the arm 60 to enclose the end of the spindle 72 and the clamping nut 77. The reel 18 is secured for rotation with the gear 75 and the spindle 72 by a pin 97 carried by the gear 75 upon the left face of the hub portion thereof, as viewed in Fig. 6, which is designed to enter openings provided in either of the flanges 63 of the reel.

Referring to Figs. 1 and 2, the arm 60 above the head portion 71 thereof pivotally supports a handle 101 provided with a pin 102 arranged to rest, when the arm 60 with the attached reel is in an operative position, as shown in full lines in Figs. 1 and 2, against a substantially vertical surface 103 formed upon a bracket 104 secured to the frame 17. In this position the gear 75 and its associated gear 38 or 39 are operatively engaged. In the operation of the apparatus when a filled reel is to be removed from its driving spindle and replaced with an empty one, the handle 101 is grasped by the operator and rocked about its pivot as viewed in Fig. 2 in a clockwise direction, the pin 102 riding upon an inclined surface 105 upon the bracket 104, the arm 60, it will be understood, is rocked about its pivot 61 in unison therewith and thus disengages the gear 75 from its associated gear 38 or 39 carried by the driving spindle 35.

65 The reels when filled with wire are quite heavy and to relieve the operator from the strain incident to holding the filled reel 18 and the arm 60 from falling, due to the force of gravity, when the arm passes the vertical position during the rocking thereof 70 in a clockwise direction about its pivot 61 and for holding the arm in a predetermined lowered position, a friction link device 108 is provided. The device 108 comprises a pair of pivotal links 109 and 110, which, as indicated at 111 and 112 (Fig. 2) are pivoted to the frame 17 and the upper end of the arm 60, respectively. The opposite ends of the links 109 and 110 are bifurcated and pivotally connected together by a bolt 113 passing through circular openings provided in the arms thereof, the arms of the link 109 being positioned outside of the arms of the link 110. Mounted upon the bolt 113 between one arm of the link 110 and a nut 80 115 threaded onto the bolt 13 is a circular spacing collar 116. The diameter of the collar 116 and the head of the bolt 113 are substantially the same and are adapted to freely rotate within the openings in the arms of the link 109. Rotatably carried upon the bolt 113 between the arms of the link 110 is a latch disc 118 provided with a plurality of teeth 119. Also carried upon the bolt 113 at either side of the disc 118 are 85 discs 120 composed of any suitable friction material. It will be apparent that by turning the nut 115 upon the bolt 113 the arms of the link 110 with the discs 118 and 120 therebetween may be compressed to cause the 90 friction discs 120 to grip the opposite surfaces of the latch disc 118 with a suitable pressure. A spring pressed plunger 121 is carried in a recess provided in the bifurcated end of the link 109, the outer end of the plunger being adapted to engage the peripheral toothed surface of the latch disc 118. Referring to Fig. 2 of the drawings wherein one of the arms 60 associated with the lower unit 16 and its associated parts is shown in dotted outline in its lowered position, it will be apparent that upon rocking the arm 60 in a clockwise direction about the pivot 61, as hereinbefore described, the links 109 and 110 will turn in opposite directions about 100 the bolt 113. The link 109 in turning upon the bolt 113 during the travel thereof from the full line to the dotted line position (Fig. 2) will rotate the latch disc 118 therewith, due to the plunger 121 engaging a tooth 119 thereof, and the friction set up between the friction discs 120 engaging opposite surfaces thereof is sufficient to restrain the arm 60 and the loaded reel 18 carried thereby from the normal force of gravity. The 105 length of the links 109 and 110 and their pivotal point upon the frame 17 and arm 60 are such that no relative movement between the latch disc 118 and the friction discs 120 occur to retard the free movement of the 110

tionary lug 165 fixed to the frame 17 serves to urge the friction ring 37 toward the right and against the friction clutch face 33. In operation it will be apparent that the compression of the spring 162 in response to a clockwise movement of the rocker arm 156 about its pivot will reduce the force of the spring 163 acting to urge the friction clutch faces together and thereby lessen the driving pressure therebetween.

Upon a reverse movement of the rocker arm taking place the spring 163 in response to an expansion of the spring 162 will cause an increase in the driving pressure between the clutch faces. The compression of the springs 162 and 163 are variable by adjusting the nuts 161 and 164, respectively, upon the link 158.

The wire is distributed upon the take-up reel 18 in timed relation to the feeding of the wire from the capstan (not shown) to the take-up reel by the movement of a pair of spaced blades 168 of the wire distributing mechanism 19 (Figs. 1 and 2) which are reciprocated back and forth across the winding on surface of the reels 18 in a horizontal direction and at a predetermined speed by the following mechanism. Upon the left end of the main drive shaft 23 associated with the upper reeling unit 15 (Figs. 1 and 2) is a sprocket 169 operatively connected to a sprocket wheel 170 by a chain 171, the sprocket wheel 170 being fixed to a stub shaft 172. Also fixed to the shaft 172 is a gear 173 meshing with a gear wheel 174 secured to a shaft 177 which has secured thereto a worm 178. The worm 178 meshes with a worm wheel 179 fixed to a shaft 180 having secured thereon a heart shaped box cam 181. Reciprocally mounted in journals 184 is a rack bar 185 carrying a roller 186 arranged to ride within the box cam 181. Meshing with the teeth of the rack bar 185 is a gear 187 secured to a shaft 188 suitably journaled upon the frame 17, the shaft 188 also having secured thereto a gear wheel 189 meshing with a second rack bar 190 suitably journaled for vertical reciprocation upon the frame 17. The rack bar 190, in addition to the teeth provided thereon for meshing with the gear wheel 189, is provided with oppositely disposed teeth which mesh with a pair of gears 193, one for each of the reeling units 15 and 16, the gears 193 each being secured to one end of a shaft 194 rotatably mounted in journals 195. Secured to the opposite end of each of the shafts 194 is a gear 196 similar to the gear 193 and which meshes with a horizontally reciprocal rack bar 197 carried upon journals 198 at the front of the frame 17.

Each pair of wire distributing blades 168 hereinbefore referred to are adjustably mounted upon their associated rack bar 197 in such a manner that by rotating a thumb screw 199 operatively associated with the means for mounting the blades upon the

rack bar 197 they may be accurately adjusted with respect to the flanges of the reel 18. It will be apparent that upon the shaft 23 being set in motion, the distributing blades associated with each pair of reels 18 of the reeling units 15 and 16 will be reciprocated back and forth, at a suitable speed, across the winding on surface of the reels 18 by the cooperating sprockets 169 and 170, gears 173, 174, 187, 189, 193 and 196, worms 178 and 179, cam 181, roller 186 and racks 185, 190 and 197, as just described.

Upon transferring the traveling wire from a filled reel to an empty one during the continued operation of the reeling apparatus, means is provided intermediate the two reels of each unit and rotatable in unison therewith for catching the oncoming wire and causing it to travel with the reels during the continued rotation thereof. The wire catching means comprises a circular disc 200, having fixed thereto at its center a pin 201 which is entered within the bore of the sleeve 78 secured to the spindle 72 (Figs. 1, 2 and 6). The pin is provided with a plurality of slots 202 cut at right angles across its diameter with the split portions of the pin 201 fitting the bore of the sleeve 78 with a spring action, but in such a manner that it with the attached disc may be readily removed from the associated reel 18 and similarly associated with the oppositely disposed reel. Formed in the periphery of the disc 200 are a plurality of equally spaced notches or depressions 203. In transferring the traveling wire from a filled reel to an empty one, the length of the wire spanning the space between the two reels will enter one of the notches 203 and be carried around with the disc 200 and the reels and thus it will be apparent the oncoming wire will be wound upon the new reel. During the winding of the new reel the wire spanning the two reels is severed in any suitable manner and the filled reel may then be removed from its spindle and an empty one mounted thereon in the manner hereinbefore described. If the wire catching disc is mounted upon the removed reel it may be readily detached therefrom and associated with the revolving reel being filled before the empty reel substituted for the filled reel is mounted upon its driving spindle.

The operation of the apparatus is as follows:

The following description of operation will be confined to the unit 16, but it will be apparent that it also applies to the unit 15 with the exception that the wire in passing from the guide pulley 125 to the unit 15 125 is associated with its respective clutch governing device by being threaded therearound upon leaving the pulley 125 in a counter-clockwise direction, as is clearly shown in Fig. 1 of the drawings. Refer-

ring now to the unit 16, the wire from the pulley 125 is given several complete wraps around the sheave 130 in a clockwise direction (Figs. 1 and 5) and then around the 5 right end of the sheave 143 mounted perpendicular to the sheaves 130 and 131 and thence onto the sheave 131 and wrapped therearound several times in a counter-clockwise direction. The wrapping of the 10 wire around the sheaves 130 and 131 it will be apparent provides a storage for the wire which is primarily necessary due to the wide range of variation in speed of the take-up reel during the transferring operation 15 which will be described hereinafter. The end of the wire is then threaded between the distributing blades 168 and secured in any suitable manner to one or the other of the reels 18. The reel 18 is then rotated clockwise 20 as viewed in Fig. 2 for a suitable distance by hand to impart a normal operating tension upon the wire between the capstan (not shown) and the reel 18. This it will be apparent causes the rotation of the 25 sheave 131 counter-clockwise and through the loop of wire running around the sheave 143 supported upon the housing 132 rotates the latter in the same direction, as viewed in Figs. 1 and 4. The housing 132 being 30 fixed to rotate with the spindle 126 carries the latter with it and thus the cam 144 assumes the normal operating position shown in Fig. 10 of the drawings with the roller 145 positioned upon the cam intermediate 35 the high and low points thereof, in which position the lower surface of the cam 152 of the lever 146 is engaged with the long arm of the bifurcated lever 147. In this position of the governing device, a suitable normal driving pressure occurs between the opposed faces of the friction clutch. 40

The reeling apparatus is then set in motion and thus the take-up reels 18 and the wire distributing blades will operate in the 45 manner hereinbefore described. As the diameter of the reel increases as each layer of wire is wound thereon it becomes necessary to gradually increase the driving pressure between the friction faces of the clutch 50 to maintain the predetermined tension on the wire which otherwise would become slack between the reel and the capstan, the wire being delivered at a constant speed to the reeling apparatus. During the building 55 up of the take-up reel in diameter the clutch governing device operates in the following manner. The energy stored in the clock spring 135 immediately upon any tendency of the wire to slacken, which momentarily 60 occurs at the completion of each layer of wire wound, at which instant, the wire moves further out from the axis of the reel to form the next layer, slightly rotates the housing 132 and spindle 126 as viewed in 65 Figs. 1 and 4 in a clockwise direction.

Thus through the cam 144 fixed to the spindle 126 and the associated system of sensitively balanced levers (as hereinbefore described), the driving pressure between the friction clutch faces will be gradually increased and consequently the driving power applied to the take-up reel will gradually become greater, but it will be apparent that the rotative speed of the reel will be gradually decreased therewith as a result of the 75 increasing diameter of the reel, the slippage between the clutch faces becoming greater as the reel builds up. When the reel being filled is wound with sufficient wire, the operator draws the traveling wire from between the associated distributing blades 168, preferably at an instant 80 when the blades are adjacent the outer flange of the reel, and inserts it between the blades 168 associated with the empty reel which at this instant are disposed adjacent the inner flange of the empty reel, each set of blades traversing in unison the faces of the associated reels. As hereinbefore described, the length of wire spanning the space between the two reels enters one of the notches 203 in the disc 200 and is carried around therewith and thus the winding of the wire upon the empty reel commences. 90

At the instant of transferring the oncoming wire from the filled reel to the empty one it will be apparent from the description of operation heretofore given in connection with the building up of the filled reel, that the driving pressure between the friction clutch faces has been gradually increased and the rotative speed of the reels has been correspondingly reduced. Since the two associated reels of each unit are operated in 100 unison from the same friction clutch and the wire is being moved from a winding on surface of large diameter to one of a much smaller diameter, it will be evident that to maintain the predetermined tension upon the wire, the driving power applied to the reel should be reduced to correspond with the diameter thereof through a correspondingly reduced pressure between the friction clutch faces. At the same time the speed of the 105 reel will reach its maximum due to the reduced slippage between the clutch faces caused by the reel being empty and the winding on point of the wire being relatively close to the axis of the reel. It will be apparent that the wire will tend to slacken between the capstan (not shown) and the empty reel upon the transfer thereof from the filled reel to the empty one but this 110 slackening is prevented by the continued rotation of the housing 132 clockwise under the action of the clock spring 135 and co-operating mechanism. As hereinbefore described, this movement of the housing 132 115 serves to increase still further the driving 120

125 130 135

pressure between the clutch faces and thereby the driving power applied to the reel becomes greater, which results in a rapid increase in the take up of the wire in excess 5 of the speed at which the wire is being delivered by the capstan, and consequently the wire is drawn from the storage provided for by the sheaves 130 and 131, as hereinbefore described. This rotates the housing 132

10 counter-clockwise and thus the clutch pressure is reduced a suitable degree to maintain the predetermined tension on the wire, the reeling operation proceeding as hereinbefore described. It will be understood the length 15 of the spring 135 is such that no substantial difference in tension occurs therein within the range of movement of the housing 132 during the reeling and transfer operations.

In case the wire breaks during the reeling 20 operation the friction clutch faces are disengaged in the following manner. The normal tension upon the wire during the reeling thereof exerts a pull upon the housing 132 in a counter-clockwise direction against the 25 force of the clock spring 135. When the tension in the wire is released by the breakage thereof the clock spring 135 pulls the housing 132 very quickly in a clockwise direction, the cam 144 (Figs. 10 and 11) being operatively connected thereto moves therewith. During this movement the roller 145 riding upon the face of the cam 144 rocks the lever 146 clockwise and through the spring 153 the lever 147 follows, the 30 levers 146 and 147 pivoting about the pin 149 and thereby momentarily causing an increase in the pressure between the clutch faces in a manner similar to that described heretofore. Upon the closed end of the cam 35 face striking the roller 145 the lever 146 is lifted upwardly, rocking the lever 147 counter-clockwise and thereby expanding the spring 153 until a force is exerted downwardly by the lever 146 and the roller 145,

40 resting at this time at the closed end of the cam face sufficient to arrest the movement of the housing 132 clockwise (Fig. 11). This movement of the lever 147 rocks the arm 156 clockwise and through the cooperating 45 mechanism compresses the springs 162 and 163 and rocks the lever 58 clockwise sufficiently to cause a disengagement of the clutch faces and consequently a stoppage of the apparatus. In the position of the cam 50 144 as shown in Fig. 11, there occurs a balancing of forces between the springs 135 and 153 due to the wire breaking which leaves the mechanism in the position shown and the clutch faces disengaged until the break in 55 the wire has been repaired and the wire properly strung upon the apparatus.

What is claimed is:

1. In a strand reeling apparatus, a take-up reel, means for communicating power there-

to, means including rotatable members having fixed axes of rotation engaged by and responsive to the action of the strand, and an elastic leverage mechanism operatively connected thereto and with the power communicating means to vary its action in response to any tendency of the tension in the strand to vary from a predetermined amount.

2. In a strand reeling apparatus, a take-up reel, means for communicating power thereto, a plurality of elements engaging the strand having fixed axes of rotation, a rotatable tensioned element, the strand running over the elements to the take-up reel, and an elastic leverage mechanism operatively connected at one end with the power communicating means to vary its action in response to any tendency of the tension in the strand to vary from a predetermined amount.

3. In a strand reeling apparatus, a take-up reel, power driving means therefor including friction discs, a pressure spring for maintaining the discs in driving engagement, means having fixed axes of rotation engaging the strand as it travels to the take-up reel, and a leverage mechanism including an elastic member operatively connected to the rotatable means and with the pressure spring to vary the pressure thereof and thereby the driving pressure of the friction discs in response to any tendency of the tension in the strand to vary from a predetermined amount.

4. In a strand reeling apparatus, a take-up reel, power driving means therefor including friction discs engaging each other face to face, a pressure spring for maintaining the discs in driving engagement, means having fixed axes of rotation engaging the strand as it travels to the take-up reel, and a leverage mechanism including an elastic member adapted to resist pressure operatively connected to the rotatable means and with the pressure spring to vary the pressure thereof and thereby the contact pressure of the friction discs in response to any tendency of the tension in the strand to vary from a predetermined amount.

5. In a strand reeling apparatus, a take-up reel, friction driving means therefor, a plurality of elements having peripheral strand guiding faces and fixed axes of rotation engaging the strand as it travels to the take-up reel, and an elastic leverage mechanism operatively connected to the elements and with the friction driving means to vary the driving pressure thereof in response to any tendency of the tension in the strand to vary from a predetermined amount.

6. In a strand reeling apparatus, a take-up reel, driving means therefor, a plurality of sheaves having fixed axes of rotation and

another sheave mounted with its axis perpendicular and movable with respect thereto over which the strand running over the sheaves to the take-up reel passes for controlling the driving means in response to any tendency of the tension in the strand to vary from a predetermined amount.

7. In a strand reeling apparatus, a take-up reel, friction driving means therefor, a plurality of sheaves having fixed axes of rotation, another sheave mounted with its axis perpendicular thereto and revolvable thereabout, elastic means connected thereto for resisting the movement thereof, the strand running over the sheaves to the take-up reel, and an elastic leverage mechanism operatively connected to the elastic means and with the friction driving means to vary the driving pressure thereof in response to any tendency of the tension in the strand to vary from a predetermined amount.

8. In a strand reeling apparatus, a take-up reel, friction driving means therefor, means having fixed axes of rotation responsive to the strand for continuously storing a progressively increasing length of strand during the reeling operation, and an elastic leverage mechanism operatively connected thereto and with the friction driving means to vary the driving pressure thereof in response to any tendency of the tension in the strand to vary from a predetermined amount.

9. In a strand reeling apparatus, a take-up reel, means for communicating power thereto, a plurality of sheaves responsive to the advancement of the strand to the take-up reel, means operated by the portion of strand between said sheaves, and an elastic leverage mechanism operatively associated with said means and with the power communicating means to vary its action in response to any tendency of the tension in the strand to vary from a predetermined amount.

10. In a strand reeling apparatus, a take-up reel, means for communicating power thereto, a plurality of rotatably mounted spaced sheaves, a yieldably mounted strand guiding element therebetween eccentric of the axis thereof and revolvable thereabout, the sheaves and element responsive to the movement of the strand running to the take-up reel, and a leverage mechanism operatively connected to the element and with the power communicating means to vary its action in response to any tendency of the

tension in the strand to vary from a predetermined amount.

11. In a strand reeling apparatus, a take-up spool, means for communicating power thereto, a pair of sheaves, a third sheave intermediate said sheaves supporting the strand between said other sheaves and responsive to the advancement of the strand to the take-up reel, and an elastic leverage mechanism operatively associated with the intermediate sheave and with the power communicating means to vary its action in response to any tendency of the tension in the strand to vary from a predetermined amount.

12. In a strand reeling apparatus, a take-up reel, friction driving means therefor, a plurality of spaced elements having fixed axes of rotation designed to continuously provide a storage for a length of strand during the reeling operation intermediate the supply and the take-up reel and over which the strand runs to the reel, strand guiding means interposed between the spaced elements upon an axis perpendicular thereto and revolvable therearound, a length of the strand being wrapped around one of the spaced elements in one direction, passed over the interposed guiding means and wrapped in an opposite direction around the other spaced element and thence to the reel, elastic means connected to the guiding means for resisting the movement thereof, and an elastic leverage mechanism operatively connected to the elastic means and with the friction driving means to vary the driving pressure thereof in response to any tendency of the tension in the strand to vary from a predetermined amount.

13. In a strand reeling apparatus, a take-up reel, means for communicating power thereto, means having fixed axes of rotation engaged by and responsive to the action of the strand, and an elastic leverage mechanism operatively connected thereto and with the power communicating means to vary its action in response to any tendency of the tension in the strand to vary from a predetermined amount, and means operatively connected to the leverage mechanism for causing the power communicating means to become inoperative in the event that the wire breaks.

In witness whereof, I hereunto subscribe my name this 22nd day of June A. D., 1926.

JOHN NILSEN SELVIG.
